Primary Examiner — Cathron C Brooks*Assistant Examiner* — Sharon S Oum(74) *Attorney, Agent, or Firm* — McGarry Bair PC(57) **CLAIM**

The ornamental design for a ceiling fan motor housing, as shown and described.

DESCRIPTION

FIG. 1 is a top perspective view of a ceiling fan motor housing shown in the environment of a ceiling fan, showing our new design;

FIG. 2 is a bottom perspective view of the ceiling fan motor housing of FIG. 1;

FIG. 3 is a side view of the ceiling fan motor housing of FIG. 1;

FIG. 4 is a top view of the ceiling fan motor housing of FIG. 1; and,

FIG. 5 is a bottom view of the ceiling fan motor housing of FIG. 1.

The broken lines illustrate portions of the ceiling fan motor housing and illustrate the ceiling fan environment. None of the broken lines form part of the claimed design.
